UNITED STATES PATENT OFFICE

169,326

FISH LURE

Thomas A. Patrick, Detroit, Mich.

Application January 28, 1952, Serial No. 18,261

Term of patent 14 years

(Cl. D31—4)

To all whom it may concern:

Be it known that I, Thomas A. Patrick, a citizen of the United States and a resident of the city of Detroit, county of Wayne, State of Michigan, have invented a new, original, and ornamental Design for a Fish Lure, of which the following is a specification, reference being had to the accompanying drawing, forming a part hereof, in which:

Fig. 1 is a side elevational view of a fish lure showing my new design;

Fig. 2 is an edge view thereof.

I claim:

The ornamental design for a fish lure, as shown.

THOMAS A. PATRICK.
